UNITED STATES PATENT OFFICE.

DAVID E. HIPOLITO, OF SAN JOSE, CALIFORNIA.

REVERSIBLE WINDOW.

No. 865,340.

Specification of Letters Patent.

Patented Sept. 3, 1907.

Application filed February 18, 1907. Serial No. 358,125.

To all whom it may concern:

Be it known that I, DAVID E. HIPOLITO, a citizen of the United States, residing at San Jose, in the county of Santa Clara and State of California, have invented new 5 and useful Improvements in Reversible Windows, of which the following is a specification.

This invention relates to that class of windows in which supplemental stiles or shoes are pivoted to the outer edges of the stiles of the window sash.

10 The object of this invention is to provide a reversible window having a minimum number of parts of maximum simplicity and ease of construction and assemblage.

15 The accompanying drawings illustrate the invention:—

Figure 1 is a broken view in elevation of a window constructed in accordance with this invention. The supplemental stile on one side of the window is shown in longitudinal section along the mid-length thereof.

20 Fig. 2 is a view of the edge of the sash with the supplemental stile upright and the sash turned aslant. Fig. 3 is a cross section of the stile and supplemental stile cutting axially through the pivot on line x^3 , Fig. 1. Fig. 4 is a section on line x^4 , Fig. 1. Fig. 5 is an exaggerated 25 fragmental sectional detail view of the supplemental stile detached.

1 is the stile of the window sash, the same being provided with a longitudinal groove 2 in its outer edge, said groove being deepened in the middle to form a recess 3, in which recess a pivot plate 4 is secured by screws 5. Said pivot plate may be resilient or rigid.

6 designates the supplemental stile in the form of a strip or bar provided along its inner edge with an oval tongue 7 to fit in the groove 2 which is concaved to 35 form to the tongue of the supplemental stile. Said supplemental stile is provided on its outer face with a recess 8 in which a strap or bar spring 9 is mounted, the same being preferably secured by means of screws 10 and provided with a screwthreaded hole 11.

40 12 is a pivot bolt extending through a hole 13 in the supplemental stile 6 and connecting the pivot plate 4 and the spring 9, a screwthreaded portion 14 of said bolt being screwed into the spring 9 which is in the form of a flat spring of considerable thickness at the 45 middle to afford sufficient length for the screwthreaded hole 11 to hold the pivot 12 securely. The pivot 12 is also screwthreaded at the other end 15 and is screwed into the pivot bar or plate 4. Preferably the middle of the bolt is not screwthreaded.

50 The members 4 and 9 are pivot holders, one or both of which may be resilient; said holders comprising resilient means to hold the supplemental stile against the stile, and the rounded or oval tongue in engagement with the groove, so that when the sash is completed the 55 supplemental stile and the stile on each side of the sash

will be fitted together by tongue and groove means, open space being provided at the middle of the recess 8 as shown, to allow sufficient movement of the resilient means to permit the tongue to move out of the groove when the frame of the window-sash is turned on its 60 pivots.

The flat spring or member 9 is of considerable length so that its ends come near the ends of the supplemental stile, so that the tension is applied to the supplemental stile near enough the ends thereof to hold the supplemental stile true and to avoid springing or warping away from the stile. Each stile of the window is similarly constructed and provided with a supplemental stile.

70 The supplemental stile springs 9 will normally bow away from the shoes at the middle, as indicated in Fig. 5.

In practice, to assemble the window, the pivot-plate 4 will be secured in place by screws 5, one end of the pivot-bolt 12 will be screwed thereinto, and the supplemental stile spring 9 will be secured in place by its 75 screws 10. The pivot-bolt 12 normally projects far enough outward from the pivot-plate 4 to pass through the hole 13 in the supplemental stile and enter the screw-threaded hole 11 in the supplemental stile spring 9, while the tongue 7 of the supplemental stile is 80 outside the groove 2 of the stile; so that the screw may be well started into the supplemental stile spring 9 before any tension is brought upon the resilient means to force the tongue into the groove. The operator will then turn the supplemental stile around on the pivot-bolt 12 until the tension of the resilient means is sufficient to hold the tongue 7 firmly, though removably, in groove 2 when the supplemental stile is brought into line with the stile 1. In Fig. 1, all tension desired may be given by turning the supplemental stile around a 85 sufficient number of times on the pivot-bolt.

When the window is installed, it will be used in the way common with reversible windows.

The tension of the springs may be increased and diminished at any time after the sash is in the frame, by 95 simply revolving the sash in the window frame 16 until the appropriate tension is secured.

To tighten or loosen one supplemental stile without tightening or loosening the other, the sash may be detached, whereupon either supplemental stile may be 100 turned independently of the other to loosen or tighten the supplemental stile.

I claim:—

1. In a reversible window provided with a stile and supplemental stile, a pivoted plate and a spring, one fastened to the stile and the other to the outside of the supplemental stile and each provided with a screwthreaded hole, said holes being coaxial and a pivot screwthreaded at both ends and screwed into said holes. 105

2. In a reversible window provided with a stile and supplemental stile, a plate fastened to the stile, a flat spring 110

- fastened to the outside of the supplemental stile and being of considerable thickness at the middle and there provided with a screwthreaded hole and a pivot screwthreaded at its ends and screwed into said plate and spring.
- 5   3. In a reversible window, a stile, a plate fastened to said stile and provided with a screwthreaded hole, a supplemental stile provided with a hole, a spring on said supplemental stile provided with a screwthreaded hole and a pivot screwthreaded at its ends and smooth at the middle
10 inserted through the hole in the supplemental stile and screwed into said plate and spring.
4. In a reversible window, the combination with a grooved stile, of a plate secured in the groove thereof, a tongued supplemental stile, a flat spring outside the supplemental stile and a pivot screwed into the plate and 15 spring and connecting the same pivotally together.

In testimony whereof, I have hereunto set my hand at Los Angeles California this 11th day of February 1907.

DAVID E. HIPOLITO.
